UNITED STATES PATENT OFFICE.

HARRY S. PARKS, OF PHILADELPHIA, PENNSYLVANIA, ASSIGNOR TO PNEUMERCATOR COMPANY, OF NEW YORK, N. Y., A CORPORATION OF MAINE.

DISTANT BOILER-WATER-LEVEL INDICATOR.

1,421,711.

Specification of Letters Patent. Patented July 4, 1922.

Application filed April 12, 1917. Serial No. 161,545.

To all whom it may concern:

Be it known that I, HARRY S. PARKS, a citizen of the United States, residing at Philadelphia, in the county of Philadelphia and State of Pennsylvania, have invented new and useful Improvements in Distant Boiler-Water-Level Indicators, of which the following is a specification.

The present invention has for its object to provide an indicating means or apparatus for showing at a distance from a steam boiler or any pressure tank containing liquid the condition or stage or height of water or other liquid in the boiler or tank; the indication given thereby preferably showing the actual height of water in the boiler with reference to a plane denominated the normal water level. In order to show the need and utility of such a device, I will indicate some of the uses to which it may be applied. At the present time, so far as I am aware, the only practical boiler-water-level indicator is the old and universally used gage glass which is simply a glass tube set in front of the boiler so as to cross the plane of the surface of the water therein and connected at its ends with the steam space and the water space of the boiler respectively. In the operation of steam boilers, particularly those furnishing steam for power purposes, it is of the highest importance that the water be maintained in the boiler at a certain height with the least possible variation, since, if the water is allowed to rise too high in the boiler, there is danger of water being carried with the steam into the engine, while, if it is allowed to fall too low, the integrity of the boiler is endangered. At the same time the ordinary boiler gage glass, particularly in connection with lofty boilers and in the boiler rooms of ships, is necessarily frequently placed in positions so high above the floor of the boiler room, or otherwise so difficult of access, that it is a matter of great difficulty to distinguish the surface of the column of water therein. In many cases also, and this is particularly so in steamships, the boiler-water-level gages of the common type are so placed that they are not visible, or at least not clearly and easily so, to the responsible engineer in charge of the power plant.

It is the purpose of my invention to provide an indicator which can be placed at a convenient height in the boiler room where

the boilers rise to a great height, or may be placed in a different room such as the engine room, of a stationary or marine power plant, or in a separate office if desired; and so connected with the boiler and controlled by the pressures and waterheads therein as to register with accuracy the momentary water level in the boiler, whether the indicator be above or below or at the same height with the surface of the water contents of the boiler. By "momentary water level" in this connection, I mean the stage or height of the water surface in the boiler at the time when any observation is made, and I intend to signify thereby that the indication given by the indicator varies in exact proportion with the change in the height or stage of water in the boiler.

While the invention may be embodied in various forms, I have illustrated and described in this specification for the purpose of explaining the principles of the invention, one specific form which I have successfully operated and which at the present time I consider preferable to other possible forms for various reasons, among which may be named its accuracy, durability and simplicity.

In the drawings,—

Figure 1 is a diagrammatic view illustrating the essential parts of my apparatus and the manner of connecting the same with a steam boiler.

Figure 2 is an elevation of the preferred form of the indicator instrument or indicator proper of the apparatus.

Figure 3 is a side elevation of such indicator instrument.

Figure 4 is a cross section of the instrument taken on the line 4—4 of Figure 2, looking downward.

Figure 5 is a side elevation of the connector which forms part of my indicator apparatus.

Figure 6 is a plain view of such connector.

Figure 7 is a longitudinal section of the connector.

Like reference characters indicate the same parts in all of the figures.

In Figure 1 which shows diagrammatically the entire apparatus and illustrates the principles of the same, 11 represents the front end of the uppermost drum, or steam drum, of a tubular boiler and may be considered as typifying that part of any boiler

wherein the dividing surface between water and steam lies. 12 represents the ordinary gage glass of such boiler, which may be retained and used if desired in connection with 5 my indicating apparatus. In applying my indicating apparatus to boilers already installed, I find it convenient to connect parts of the same with the already existing pipes 13 and 14 which connect the gage glass with 10 the steam and water spaces of the boiler respectively, whereby to put the apparatus in communication with these spaces.

My novel apparatus comprises a pipe line 15, a second pipe line 16, a connector 17 15 (shown in detail in Figures 5, 6 and 7) and an indicator instrument 18 (shown in detail in Figures 2, 3 and 4). The connector has provision at 19 (Fig. 7) for making connection with the pipe line 15, and similar 20 provisions at 20 for connecting with the pipe line 16, these provisions being conveniently tapped holes in the lower side of the connector as shown in Figure 7. Similar provision is made at 21 for connection with 25 a pipe 22 which makes communication with the steam space of the boiler, conveniently by being joined to the steam connection 13 of the gage tube 12. A useful detail of construction, consists in the provision in 30 side the connector of an internal ledge 23, surrounding the inner orifice of the hole 19, and the provision of fins 24, 25, on the exterior of the connector, on opposite sides of the same, and in the same plane 35 with said ledge. These fins are simply indices by which the position, or height with respect to the boiler water level, of the ledge may be indicated when the apparatus is installed. A pipe 26 joins the pipe line 16 40 with the water space of the boiler, preferably by being connected with the water connection 14 of the gage glass, or otherwise if desired.

At one end of the connector is an outlet 45 171, controlled by a stop cock 172, from which a drain tube 173 leads. This outlet is for the purpose of discharging any air which may collect in the pipe 22 and in the connector, which would have the effect 50 of preventing flow of steam in pipe 22.

In installing the apparatus, it is essential that the ledge 23 should be above, or at least not below, the normal water level of the boiler and that the connection 26 should 55 join the pipe line 16 at a point below such level.

The form of indicator here shown comprises an outer tube 27 and an inner tube 28 of transparent material, which practically 60 must be glass, although I do not limit my patent protection for this part of the invention to that specific material, the former being closed at its upper end and the latter being open at both ends. These 65 tubes are mounted in a frame 280, the pre-

ferred form of which is indicated in Figures 2, 3 and 4, such frame having lugs 29 by which it may be attached to a wall or board. The bottom of the frame is formed as or with a tubular portion 30 which is 70 internally threaded and receives a base plug 31 which is complementally threaded externally at its upper end. The base plug has in its end a recess 32 containing a washer 33 of rubber or other material which is soft, 75 yielding and may be made impervious to water. This washer supports the open lower end of the outer tube 27 and makes water-tight contact with the edge thereof.

The upper end of the frame 280 has a 80 similar tubular portion 34 into which is screwed a plug cap 35 which has a threaded passage extending entirely through it. The upper closed end of the tube 27 extends into the part 34 and is engaged with an elastic 85 block 36 which is preferably of rubber but may be of any other soft material capable of applying pressure to the tube without injuring it. Bearing on the plug 36 is a follower 37 of a material which will withstand the effects of water and is rigid. Brass is the best material for this purpose, although any other material which will not be readily affected injuriously by water may be used. This follower is preferably counter-bored to receive the buffer block 36 to confine the latter against spreading laterally when pressure is applied to it. A set-screw 38 is engaged with the threaded passage in the cap and bears on the follower 37, being adapted to exert sufficient pressure thereon to hold the tube 27 firmly and at the same time press its lower end against the washer 33, which is also a packing, so firmly as to make a leakage-tight joint at that 95 point. The opening in the upper sleeve-like portion 34, into which the cap 35 is screwed, is large enough to permit the tube 27 and the follower 37 to be passed through it.

The inner tube 28, open at both ends, is 100 connected at its bottom end by means of a flexible section of tubing 39 with a rigid tube 40 secured to the base and projecting upward therefrom, and its upper end is steadied by a stem or stud 42 which is secured to the interior of the outer tube on the end wall thereof and projects into the inner tube. This stem is preferably of rubber although it may be of any other material sufficiently soft as not to break such brittle substances as glass when forcibly struck thereby. In addition to holding the upper end of the inner tube steady and away from the walls of the outer tube, this stud has an additional function which will later be described.

In the base plug 32 are two passages indicated at 43 and 44 respectively, the former of which opens into the tube 40 and thence to the inner indicator tube 28, and the latter 130

opens into the recess 32 and thence to the outer indicator tube 27. The passage 43 joins a lateral passage 45 having two branches 46 and 47 respectively, at the junction of which is a three-way cock 48. Similarly the passage 44 is joined to a lateral passage 49 having branches 50 and 51 and controlled by a three-way cock 52. The pipe line 16 is attached by a suitable coupling 10 to the part of the base plug which contains the branch 46, while the pipe line 15 is similarly connected to that part which contains the passage 50. The branches 47 and 51 are exhaust outlets which discharge into drip pipes 53 and 54, which may have a common outlet if desired. Stop cocks 56 and 57 are provided near those ends of the pipe lines which are connected to the indicator in order to close such lines when the 20 indicator is disconnected therefrom.

In operation the pipe lines 15 and 16 are substantially filled with water. When first setting up the apparatus, it is desirable to fill them in advance of operation in order 25 to shorten the time which must elapse until the apparatus is in full working order, but, even without this, they will quickly fill with water, the line 15 from condensation of steam flowing therein from the boiler, and the line 16 by the water which is forced 30 directly from the boiler. Assuming that the stop cocks 56 and 57 are open and the three-way cocks 48 and 52 are set so as to connect the pipe lines 15 and 16 with the outer tube and the inner tube respectively of the indicator, then the steam pressure of the boiler will force water from the pipe lines into these tubes, compressing the air entrapped therein until the pressure of compression is equal to the boiler pressure plus or minus the difference in head between the boiler and the indicator according as the indicator is below or above the boiler, respectively. Since both tubes are in free communication at their upper portions, the pneumatic pressures in both will be the same, but the water levels in the two tubes will be different owing to the difference in head or height of the columns in the pipe lines 15 and 16. In the line 15, the column rises to the height of the ledge 23, which, as previously stated, is above the normal boiler-water level, wherefore said line 15 is the high column line. Condensation of steam from the boiler maintains the head of this column at the height of the ledge and this height is fixed. Such condensation takes place in the pipe 22, and to insure that enough steam will be so condensed to maintain the column up to the level of the overflow, the pipe 22 is carried out in the form of a loop away from the boiler. The column cannot rise any higher than this because all excess of water over-flows the ledge and 65 runs through the connection 17 into the pipe

line 16. Said connection is thus in effect an overflow from the head of the column in the line 15. In the pipe line 16, however, the column of water rises only to the height of the actual momentary water level in the 70 boiler, by reason of the fact that this line is connected above the top of the column through the connector 17 with the steam space of the boiler, and is connected at a point below the boiler water level with the 75 water space of the boiler, wherefore the line 16 is the low column pipe line. There is thus a difference in head between the columns in the two pipe lines, and this difference is shown in exact ratio in the indicator, for the 80 water level in the outer tube is higher than the level in the inner tube by exactly this difference. Since both water columns are acted upon by the same steam pressure at their heads, and are balanced by the same 85 equal pneumatic pressure in the indicator, the difference in head between the two columns is free to produce a corresponding difference between the levels of water in the two tubes of the indicator, and, when the 90 height of the column in the pipe line 16 changes, the height of the water column in the inner tube of the indicator changes equally and almost simultaneously. This result is obtained whatever may be the position of the indicator, whether it is above or below or at the same level with the surface of the water in the boiler. The only limit to the position of the indicator is that it cannot be placed above the height to which the 95 boiler pressure will force a column of water, but it can be placed at any depth below the boiler, theoretically without limit and practically limited only by the power of the indicator and connections to withstand the 100 internal pressure.

It will be noted in Figure 1 that the tubes or pipe lines 15 and 16 are separated at all points not only from the boiler, but also from external contact with the boiler steam; in 110 other words, they are insulated by the air surrounding them from the heat of the steam. This insulation of the pipe lines from heat is an essential characteristic of the invention, although whether the insulation is caused by a surrounding body of air or by other means is not material, since it insures that the water in the pipes will be at a temperature far below the boiling point, and that there will be no danger of vitiating 115 the readings of the instrument by generation of steam in either or both of the pipe lines.

Preferably I provide a scale in connection with the indicator so as to show by direct 125 reading a variation of the momentary water level without requiring a comparison between the levels in the two tubes. Such scale as shown here is a plate 59 adapted to slide on a guide 60 which is formed by 130

a plate secured to the frame 280. Said scale plate 59 has a lip 61 at one edge which embraces the guide plate 60 and at the other side has a hook 62 embracing the opposite 5 edge of the guide plate and formed with a shank on which is threaded a knurled head 63. Thereby the scale may be shifted vertically and secured in any position. This scale has a graduation mark 64 representing 10 the normal boiler-water level and an index 65 at the same distance above the normal level graduation as the ledge 23 of the apparatus is above the plane at which it is designed to maintain the surface of the water 15 in the boiler, that is the actual normal boiler-water level. In addition, there may be other graduations measuring distances above and below the graduation 64 so as to measure the actual distance by which the 20 momentary water level may rise above or fall below the normal level. When the apparatus is first put in full working order, the scale 59 is shifted until the index 65 is beside the top of the column in the outer 25 indicator tube. Thereafter the top of the column in the inner tube automatically shows in connection with the scale graduations the exact variation and the amount thereof of the momentary boiler water level 30 from the normal level in either direction. In order to facilitate the reading of the indicator, I provide a colored float 66 which rests on the column in the inner tube and is easily visible through the surrounding annular column of water in the outer tube. 35

The tubes of the indicator may readily be drained by turning the stop cocks so as to connect these tubes respectively with the drip pipes 53 and 54 and at the same time 40 shut off the pipe lines. The three-way cocks also may be set so as to shut off the indicator from both the pipe lines and the drip outlets. In opening the connections from the pipe lines to the indicator after the latter has been drained, it is possible to do so 45 in such a way that the water enters so rapidly that the momentum of the float thus suddenly raised will throw the same to the top of the indicator and possibly break it. 50 The stud or stem 42 previously described acts as a buffer for the float in such case and arrests its rise without breakage.

So many possible modifications may be made from the specific form of apparatus 55 here shown, which at the same time contain the principles of the invention, that I do not limit the invention to the details of the apparatus shown, but include modifications embodying the essential principles and capable of accomplishing essentially the same 60 results as this apparatus. Thus, for example, any form of indicator capable of showing the difference between two pressures 65 may be used. This indicator is essentially a differential gage, and in the form shown is

essentially an inverted U tube of which one of the legs is made so large as to include the other. This form is preferable to one in which the legs are side by side, particularly in steamships where changes in the 70 inclination of the ship would introduce errors in the indications of such a tube. Such errors are eliminated by the coaxial arrangement of the legs here shown. However, in place of an inverted U tube of any 75 form, I may use other types of differential gage, including those of the well known spring tube and diaphragm types, wherefore I include within my claim to protection an apparatus having any type of differential gage, recording as well as indicating gages. It is of course also understood that the connections between the pipe lines and the indicator may be reversed from that shown so that the inner tube may indicate 80 the fixed level and the outer tube the momentary level.

Likewise, in place of the specific connector 17, many other constructions may be used. It is necessary in this part of the invention 90 that the height of the column in the pipe line 15 should be limited by some means so as to remain stationary at a fixed point, while the column in the other pipe line is caused to vary with the actual momentary 95 height of the water in the boiler. To secure this result, I conceive it necessary that the tops of both columns should be exposed to the confined boiler pressure, that there should be an overflow at a fixed point above 100 the normal boiler-water level from one of the pipe lines, and that the other pipe line should be connected at a point well below such level with the water space of the boiler. And an important factor contributory to 105 the result stated is that the water from the condensing pipe 22 should drop directly into the high column pipe line 15, wherefore the point 21 at which pipe 22 joins the connector 17 is directly above the point 19 at 110 which the pipe line 15 joins the connector. However the overflow from the connector may be released and taken care of by other means than by a gravity flow into the pipe line of the variable column. It might, for 115 example, be returned directly to the boiler, or released otherwise through a trap, of which any one of several known types are available for the purpose.

The term "pipe line" includes any conduit 120 or conducting means adapted to contain pressure-transmitting fluid and to support a column of the same and transmit the pressure thereof to an indicator. So far as the invention is concerned, the pressure-transmitting fluid is not necessarily limited to water, although water is naturally the fluid which would be used. In case of the employment of another fluid having a different specific gravity, the indications registered by the in- 125 130

dicator would be proportionally greater or less than the actual variations in the boiler.

The term "tubular" as used in the claims to describe the elements 27 and 28 of the indicator is not to be understood as limiting the form of these elements in any way, whether as to size, shape, arrangement or otherwise. It has already been pointed out that these elements form essentially an inverted U tube and that any form of U tube is included within the scope of my claims. It may be also noted that in the specific type of inverted U tube indicator here shown, the outer tube is a hermetically sealed chamber, and that the inner tube is a column-containing element. Each of these tubes may have any shape in cross section, non-circular as well as circular if desired, and may be of any dimensions and relative sizes. While it is preferable that each tubular member should be of the same area in cross section throughout the greater part of its length, in order that the same scale may be used without correction in all circumstances, except for adjustment as to position according to the height at which the indicator is placed or the steam pressure which is carried in the boiler, yet it is possible to make the tubes otherwise and compensate for differences in cross section thereof at different points by suitable calibration or correction of the scale.

Included within the definition of the term "steam boiler" are included all equivalent containers in which liquid is held under the pressure of its vapor generated by heat, and the condensate of the vapor is caused to maintain a column of fixed height adapted to act upon a differential indicator, which is also acted upon by a column of the liquid rising to the height of the liquid level in the container; the apparatus otherwise having the characteristics pointed out in the claims.

What I claim and desire to secure by Letters Patent is:—

1. A means for indicating the level of water in a steam boiler comprising two rising pipe lines adjacent to one another and exposed to substantially the same external temperature, lower than the boiling point of water, one of said pipe lines being connected with the boiler below the normal water level therein, and the other rising above the said normal level and adapted to contain a high water column of fixed height, a condensing pipe leading from the steam space of the boiler and arranged mainly above the head of said high column pipe line with its discharge outlet arranged to drip into said pipe line, whereby the latter is kept full to overflowing, a separate connection below the outlet of said condensing pipe arranged to conduct away such overflow, and a differential indicator connected to the two pipe lines and adapted to show the differ-
2. An indicating means as set forth in claim 1 in which the condensing pipe extends in the form of a loop away from the boiler.
3. A boiler water level indicating means comprising in combination with the boiler, rising pipe lines, a connector between the heads of said pipe lines, one of said lines being arranged to contain a high column of water rising above the normal boiler water level, and the other pipe line being connected to the boiler below said level whereby to contain a water column rising to the height of said level, a condensing tube leading from the steam space of the boiler and extended to provide substantial condensing surface above said connector and being connected thereto over the head of the high column pipe line, whereby to discharge the condensate thereinto, a normally closed venting outlet from said connector adapted to discharge entrapped air therefrom, and an indicator instrument connected to the two pipe lines and constructed with provisions for showing the difference between the actual boiler water level and the head of the high water column.
4. The combination with a boiler of a pipe line in communication with the steam space of the boiler having an overflow outlet at a point which is located at a known level above the normal boiler water level, a second pipe line connected with the boiler below the said normal level, and a differential indicator comprising an outer chamber closed at its top and connected at its bottom with the extremity of one of said pipe lines, whereby to receive a column of water rising from said pipe line, and a column container rising from the extremity of the other pipe line within said chamber and adapted to contain also a column of water, said column container being open at its upper end and the chamber and column container both holding an entrapped body of gas above their contained columns of water.
5. An indicator instrument for measuring differences of pressure comprising an outer tube open at its lower end and closed at its upper end, rising means connected to said lower end and arranged to deliver a column of liquid to said tube, an inner tube within said outer tube and open at its upper end, and rising means connected to the lower end of said inner tube and adapted to admit a column of liquid thereto, said tubes containing an entrapped body of gas in their upper ends, opposing the rise of said liquid.
6. In a distant water level indicator, an indicator instrument comprising a frame, a base having an annular seat in said frame, a tube closed at its upper end and open at its lower end making contact with said base,

means for applying pressure to the closed end of said tube, and an inner tube within the first named tube open at both ends, said base having two passages one of which opens 5 into the first named tube and the other of which is connected with the inner tube.

7. In a boiler water level indicator, the combination with two water column containing elements, a pipe line connected with one 10 of said elements and containing a column of water which rises to an invariable height and is subjected to the steam pressure of the boiler, a second pipe line connected with the other of said elements and with the water 15 space of the boiler, whereby said elements are caused to measure the difference in head between the column in the first pipe line and the actual level of water in the boiler and a scale having graduations one of which 20 designates the normal level of water and the other is at a fixed distance therefrom proportional to the difference between the head of the column in the first pipe line and the plane of the normal boiler water level. 25

8. In a boiler water level indicator, the combination with two water column containing elements, a pipe line connected with one of said elements and containing a column of water which rises to an invariable height 30 and is subjected to the steam pressure of a boiler, a second pipe line connected with the other of said elements and with the water space of the boiler, whereby said elements are caused to measure the difference in head 35 between the column in the first pipe line and the actual level of water in the boiler, and a scale having graduations one of which designates the normal level of water and the other is at a fixed distance therefrom proportional to the difference between the head 40 of the column in the first pipe line and the plane of the normal boiler water level, said scale being adjustable along said tubular elements whereby the last named graduation 45 may be placed beside the level of the column in one of said elements.

9. A boiler water level indicator comprising two tubes each adapted to contain a water column, being in communication at 50 their upper ends with one another and connected at their lower ends with water-containing pipe lines, being otherwise hermetically sealed, and a scale adjustably mounted adjacent to said tubes and having graduations corresponding respectively to the plane 55 of normal water level in a steam boiler and a fixed point above such plane.

10. An indicator instrument comprising a frame having a base with two passages 60 through it, an outer tube closed at its upper end and fixed to said frame with its interior in communication with one of said passages and being otherwise hermetically sealed, an inner tube contained within the first-named 65 tube open at its upper end and connected

with the other of said passages, and a scale mounted beside said outer tube with provision for longitudinal adjustment.

11. An indicator instrument comprising a frame having a base provided with two passages, a compressible gasket on said base surrounding such passages, a tube having one end closed and the other end open, arranged with its open end bearing on said gasket, a follower adjustably mounted in said frame bearing on the closed end of said tube, and an inner tube open at both ends contained within the outer tube and connected at its lower end with the other of said passages. 70

12. An indicator instrument comprising a frame having a base provided with two passages, a compressible gasket on said base surrounding such passages, a tube having one end closed and the other end open, arranged with its open end bearing on said 80 gasket, a follower adjustably mounted in said frame bearing on the closed end of said tube, and an inner tube open at both ends and contained within the outer tube and connected at its lower end with the other of said 85 passages, and a float in the inner tube adapted to be supported by the column of liquid therein. 90

13. An indicator instrument comprising a frame having a base provided with two 95 passages, a compressible gasket on said base surrounding such passages, a tube having one end closed and the other end open, arranged with its open end bearing on said gasket, a follower adjustably mounted in 100 said frame bearing on the closed end of said tube, and an inner tube open at both ends contained within the outer tube and connected at its lower end with the other of said 105 passages and a stud secured to the closed end of the outer tube and projecting into the open upper end of the inner tube to hold the latter steady. 110

14. An indicator instrument comprising a frame having a base provided with two 110 passages, a compressible gasket on said base surrounding such passages, a tube having one end closed and the other end open, arranged with its open end bearing on said gasket, a follower adjustably mounted in 115 said frame bearing on the closed end of said tube, and an inner tube open at both ends contained within the outer tube and connected at its lower end with the other of said 120 passages, a float contained in the inner tube adapted to rest on the top of the column of liquid therein, and a stud secured to the closed end of the outer tube and projecting into the upper end of the inner tube 125 for holding the latter steady and also serving as a buffer for said float. 130

15. The combination with a boiler of two pipe lines, a substantially horizontal connector attached to both pipe lines and having a ledge surrounding the orifice to one

- of said lines, a connection from the upper side of said connector to the steam space of the boiler, a connection from the second of said pipe lines to the water space of the 5 boiler, and a differential indicator connected to both pipe lines.
16. A connector for a distant boiler water level indicator having an interior chamber, two connections opening into one side of 10 said chamber and one connection opening into the other side of the chamber, said connector also having a ledge surrounding the orifice of one of the two connections first named.
- 15 17. A connector for a distant boiler water level indicator having an internal chamber, two connections opening into one side of 20 said chamber and one connection opening into the other side of the chamber, said connector also having a ledge surrounding the orifice of one of the two connections first named and having an external index in the same plane with said ledge.
18. A connector for a distant boiler water level indicator having an interior chamber, 25 two connections opening into one side of said chamber, and one connection opening into the opposite side of the chamber arranged to be directly over one of the two first-named connections when the connector 30 is in operative position.
19. In a distant boiler water level indicating apparatus the combination with two substantially upright pipe lines of a substantially horizontal connector into the under side of which the upper ends of said 35 pipe lines are joined, the entrance to one of said pipe lines being raised above the interior bottom of the connector and also above the entrance to the other pipe line, 40 and a condensing pipe joined to the upper side of the connector directly over the said raised pipe line entrance.

In testimony whereof I have affixed my signature.

HARRY S. PARKS.
